CHECK-CONTROLLED MUSIC-PLAYING DEVICE

1,146,067.

Specification of Letters Patent. Patented July 13, 1915.

Application filed March 1, 1913. Serial No. 751,610.

To all whom it may concern:

Be it known that I, PAUL HÄNSEL, a subject of the King of Saxony, residing at 10 Aeussere Halleschestrasse, Leipzig - Gohlis, 5 Germany, have invented certain new and useful Improvements in Check-Controlled Music-Playing Devices; and I do hereby declare the following to be a full, clear, and exact description of the invention, such as 10 will enable others skilled in the art to which it appertains to make and use the same, reference being had to the accompanying drawings and to letters or figures of reference marked thereon, which form a part of this 15 specification.

My invention relates to check controlled music playing devices, that is to say to the mechanism for setting in operation the music playing mechanism for playing either 20 successively or selectively any one of a number of pieces of music by depositing a check or coin in a suitable apparatus either directly connected to the case of the musical instrument or at considerable distance therefrom but electrically connected thereto. The mechanism forming the subject-matter of this invention therefore has at a suitable point a control device operated by the insertion of a check or coin at a suitable point 25 or by the pressure of a controlling knob or several such devices. This mechanism is provided also with a number of starting switches for the music, such as a rotatable wheel contact device, buttons, or slidable indicators corresponding in number to the 30 number of pieces to be played. These devices can be set by the person using the player so as to play any one of a number of pieces of music on the program list, or 35 so as to play pieces successively. After setting the device for the piece of music to be played, the coin or check is inserted and the selected note sheet is brought into playing position and the automatic playing mechanism is set into operation. After the piece 40 of music has been played the parts are automatically returned to normal position. If a check or coin is inserted without operating the selecting device for selecting a certain 45 piece of music, then the next piece of music is played, that is, the pieces are played successively in the same order in which they are mounted in the magazine carrying the music 50 rolls.

Referring to the drawings in which like parts are similarly designated: Figure 1 is a diagrammatic view illustrating one form of my invention. Fig. 2 is a detail end view of the selector drum, and Fig. 3 is a diagrammatic view showing means for indicating the particular piece of music to be played.

Referring more particularly to Figs. 1 and 2, A is a suitable switch-board provided with a plurality of circuit closers $b-b^{10}$, connected in parallel with the battery B or other suitable source of electrical supply. From the source of current B there is a wire 2 leading to a circuit closer a and from said circuit closer is a wire 3 continuing to the multiple wire C of the switch-board A. The circuit closer a is of any suitable type and is operated by the insertion of a coin or check. Each circuit closer $b-b^{10}$ is connected by wire o to an electro-magnet $c-c^{10}$ which magnets are in turn connected by wires 4, in parallel, to the source of current B. Each electromagnet c is opposite a releasing latch $d-d^{10}$ pivoted at 5 and provided with a hook 6 taking over a pin 7 on a bar e . The bars $e-e^{10}$ are pivoted at 8, are 80 provided with springs 9 arranged to urge them against a selector drum g and are provided with pawls $f-f^{10}$ in operative relation to notches on said drum. At one end of the drum are a number of notches corresponding in number to the number of pieces of music to be played, namely, $h-h^{10}$. These notches are in peripheral alinement and are all arranged to be engaged by the pawl f on one lever e . k is a frame extending across all of the levers $e-e^{10}$, pivoted at 10, and provided with a bell crank lever l . If the circuit closer b is closed and the coin or check is caused to operate the circuit closer a , the solenoid c is energized to release the latch d and permit the lever e under the influence of its spring 9 to move against its drum g . This will cause the frame k to be operated and the lever l will be moved in the direction of the arrow y , Fig. 1. At the same 100 time the circuit closer a closes a circuit 40, 41, through the electric motor 39 whose belt 38 is connected by belt 37 to a belt wheel 36 on a shaft 35. On shaft 35 is a worm 34 that drives a worm wheel 33 connected to a gear wheel 32 that drives a gear wheel 31, which in turn drives the gear wheel 30 for moving the music rolls in the magazine.

The gear wheel 32 carries a pinion 42 that drives a gear wheel 43 geared to a pinion 44 on drum i whereby said drum is rotated in the direction of the arrow. The bell crank lever l has a pin 45 on which rests a lever 46, and said bell crank lever l is pulled by a spring 47 to urge the frame k downward and the pin 45 into the position shown with relation to lever 46. The lever 46 has a pawl 51 arranged to move into the path of pins 52 on the gear wheel 32. This lever is pivoted at 49 and also operates a clutch 53. The motor 39 continues its driving operation until the pawl f on lever e has entered its notch on drum i when the lever e will move still farther toward the drum under the influence of spring g , thereby raising frame k , rotating bell crank lever l on its pivot 10 to move pin 45 to the left and allow clutch lever 46 to move in the direction of arrow 50, so that its notch or seat 48 will rest on said pin to cause its pawl 51 to move sheet magazine. At the same time clutch 53 is operated to disconnect the driving wheel 36 from its shaft 35. The note sheet is drawn over the tracker bar by any suitable unwinding mechanism, or by hand. When the music has been played, the note sheet is released and wound up again on its spool and the lever l is moved to its normal position upon breaking the circuit of magnet c . The latch d being released by magnet c will move to the right under the influence of the spring E . This movement causes the under edge of the hook 6 to ride on pin 7 and cam the lever e down against the action of spring g thereby causing the lever e to be again locked by its latch d . The motor is also stopped. If the switch b remains closed and the operation is repeated by inserting another check or coin, in the device then the lever c will be again released and will cause the playing of the piece of music next in order in the machine, but if it is desired not to play the next piece of music, but to select another piece of music in the magazine, it will be necessary to operate one of the levers $e'-e^{10}$, whose pawls $f'-f^{10}$ are arranged to engage recesses in the drum g . These recesses $i'-i^{10}$ are spirally arranged on the drum and come successively into operation, consequently by opening the circuit closer b and closing any one of the other circuit closers $b'-b^{10}$, the magnet c corresponding to the circuit closer operated will be energized to retract its latch and release its lever e , so that when the drum g brings its notch into position for engagement by the lug f the drum will be stopped and the music roll carrier will also be stopped with the corresponding music sheet in playing position.

In order to indicate what piece of music has been played last, I provide the mechanism shown in Fig. 3. In the mechanism

described above the circuit closers control the movement of the note sheet magazine to play any piece of music selected from a number of such. The particular piece played is indicated by mechanism for example, a sliding or rotating indicator. This indicator therefore remains stationary indicating the piece that has just been played, and the public will assume that by inserting a check or coin that that piece will be played which is indicated by the indicator. This is not so, as it is the next highest number that will be played when the pieces are played successively. In Fig. 3 I have illustrated an indicating mechanism for correctly indicating the number of the piece of music to be played next in the succession when a coin is inserted. At a suitable place on the note sheet magazine m are two contact springs n which contact springs are closed for instance by means of levers n' , n^{10} when the note sheet has been rolled up on its spool after being played. This is done by means of a pneumatic n^5 connected by an extension n^4 to lever n^2 . These contact springs n close a circuit from a source of electric supply as a battery B to a solenoid p which solenoid p has its movable core q pivotally connected at 11 to a lever 12. This lever 12 is pivoted at 13 and limited in its movement between two stops 15 and 16 and carries a pawl 17 for operating a ratchet wheel 18 on a shaft 19, which shaft also carries an indicator hand 20. This pawl operates the ratchet 18 each time that the core q is drawn up. n^1 is a spring for urging the pawl 17 into engagement with the ratchet wheel. If it is desired to play a piece other than temporarily indicated by the hand 20, then lever n^2 is operated by hand until the hand 20 is opposite the number indicating the piece desired to be played.

I claim:

1. Mechanism for positioning the note records of musical instruments, comprising a note record magazine, a plurality of branch electric circuits, circuit closers for said circuits, a selector drum, pawls normally urged toward said drum, means to normally hold the pawls out of engagement with said drum, means in said circuits to release the pawl holding means upon completion of its circuit, and mechanism to drive the note records of the magazine and said drum.

2. Mechanism for positioning the note records of automatic musical instruments, comprising a magazine of note records, a selector drum, mechanism for simultaneously positioning the records and correspondingly driving said drum, pawls for cooperating with said drum, means to normally hold the pawls out of engagement with said drum, a plurality of branch electric circuits, a circuit closer in each circuit, electric means in each circuit for releasing a pawl holding

means to permit its pawl to move into engagement with said drum and thereby cause the driving mechanism and the records to stop their movement.

- 5 3. Mechanism for positioning the note records of automatic musical instruments, comprising a note record magazine, a notched selector drum, driving mechanism common to both the magazine and drum, a series of 10 pawls urged toward the drum and arranged to stop said drum and magazine when engaging the drum, a plurality of branch electric circuits, an electro-magnet and a circuit closer in each branch for controlling the 15 movement of a pawl, a frame operated by each of said pawls and a clutch actuated by said frame to disengage said mechanism.

4. Mechanism for positioning the note records of automatic musical instruments, comprising a note record magazine, a power circuit having a main circuit closer therein, electrically driven mechanism in said circuit for moving the note records of the magazine, a selector drum driven in unison with 20 the records, a series of pawls arranged to operate with said drum, means actuated by any one of said pawls to disconnect the record moving mechanism, branch control circuits all controlled by the main circuit 25

closer, and a separate circuit closer in each 30 control circuit, an electro-magnet in each control circuit controlling the operation of a pawl, whereby upon closing the main circuit closer the electrically driven mechanism successively positions the records, and 35 upon closing one of the separate circuit closers the pawl related thereto is caused to coöperate with said drum and stop the drum and the particular record corresponding to the position of the drum.

5. The combination with a note sheet magazine, a power circuit, a main circuit closer and electrically driven mechanism in said circuit for moving the note sheets; of a number of parallel circuits all controlled by said 45 circuit closer, a separate circuit closer in each parallel circuit and mechanism controlled by said last named circuit closers to stop said electrically driven mechanism and the note sheet magazine in accordance with 50 the separate circuit closer actuated.

In testimony that I claim the foregoing as my invention, I have signed my name in presence of two subscribing witnesses.

PAUL HÄNSEL.
